UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR CRACKING OIL

Original application filed December 9, 1920, Serial No. 429,319. Divided and this application filed May 9, 1925, Serial No. 29,142. Renewed March 10, 1931.

This invention relates to improvements in process and apparatus for cracking oil, and refers more particularly to a process in which the oil is distilled under heat and pressure, certain of the vapors subjected to reflux condensation and subjected to further cracking, the object in the present instance being to subject the reflux condensate to different conditions of temperature or pressure or both than that to which the raw oil is subjected. 5 Another object of the invention is to, if desired, subject part of the apparatus to vacuum action. This application is a division of my application Serial No. 429,319 filed December 9th, 1920 which has since eventuated 10 in Patent No. 1,537,593.

In the drawing, the single figure designates a view partly in vertical section and partly in side elevation of my improved apparatus.

Referring to the drawing, 1 designates a 20 furnace, provided with combustion chambers 2 and 3, separated preferably by a flamed bridge wall 4 inside. In the respective combustion chambers are mounted the heating coils 5 and 6, each of which may 25 take the form of a continuous length of several hundred feet of two- to eight-inch pipe. The lower coil 5 is connected by feed line 7 to charging pump 8, leading to any suitable 30 source of raw oil supply, as for example fuel oil or heavy asphaltic crudes such as California or Mexican crudes containing in themselves little gasoline, or the like. The delivery side of the coil 5 is connected by 35 transfer line 9, having throttle valve 10 and pressure gauge 11, to the end of an elongated horizontally disposed expansion chamber 12. This expansion chamber may for example be 68 inches in diameter and 40 to 60 feet long. 40 It is located outside the fire zone and suitably supported above the furnace by means of supports 13. The delivery side of the coil 6 is connected by auxiliary transfer line 14, having 45 throttle valve 15 and pressure gauge 16 to the main transfer line 9. The expansion chamber 12 is provided with residue draw off pipe 17, having throttle valve 18, and with a vapor outlet pipe 19, having throttle valve 20, leading to the lower side of the dephlegmator 50 21. The dephlegmator 21 is provided with

a series of baffle-like plates 22, and at its lower side is connected to reflux return line 23, having throttle valve 24, and leading to reflux oil pump 25 interposed in the feed line 26 leading to the inlet side of the heating coil 6. The upper end of the dephlegmator is connected by vapor line 27, having throttle valve 28, to the top of condenser coil 29, seated in condenser box 30. The lower end of the coil 29 is connected by pipe 31, having throttle valve 32, to the upper part of receiver 33. This receiver 33 has liquid level gauge 34, pressure gauge 35, liquid draw off pipe 36, controlled by valve 37. It is also provided with two gas outlet pipes 38 and 39, controlled by throttle valves 40 and 41 respectively. The pipe 39 is connected to a 55 vacuum pump 42, whereby a vacuum may be maintained on the receiver, condenser, dephlegmator and vapor chamber, or on the receiver alone or receiver and condenser alone, or receiver, condenser and dephlegmator alone. This is accomplished by suitably regulating the various valves shown. The dephlegmator is provided with pressure gauge 43 and the vapor chamber with pressure 60 gauge 44. 65

The process may be carried out as follows:

Fuel oil, as for example fuel oil from the Wayside Kansas field of say 25 degrees Baumé, may be heated to a temperature of say 700 degrees F., and subjected to a pressure of say 135 pounds in the heating coil 5, and delivered in substantially liquid phase through the insulated transfer line 9 to the expansion chamber 12. This expansion chamber may be maintained under a pressure of say 135 pounds or as hereinafter pointed out, it may be maintained under a vacuum. The reflux condensate may be pumped back by pump 25 to the heating coil 6, and there subjected to a pressure of 175 pounds and a temperature of say 770 degrees F. It is delivered in substantially liquid phase to the vapor chamber 12. 80 85 90

It will be thus seen that the reflux condensate is continuously subjected to recracking, but at different conditions of temperature or pressure, or both, than that to which the raw oil is subjected. A process may be carried out in the apparatus in the manner 95 100

just above described, except that the dephlegmator, condenser and receiver, instead of being under a pressure of 135 pounds as in the first case, may be subjected to a vacuum through suitably regulating the vacuum pump, opening the valve 41, closing the valve 40, and regulating the valve 20, valves 28 and 32 being also open.

Having thus described the invention, what I claim is:

1. A process of oil conversion, consisting in maintaining a body of heated hydrocarbons in an enlarged zone where substantial vaporization occurs, in maintaining said zone under a pressure below atmospheric, in subjecting the vapors to reflux condensation to condense the heavier vapors, in passing the reflux condensate in an advancing stream through a heating zone where it is subjected to cracking conditions of temperature and pressure, in delivering the heated condensate to said enlarged zone and simultaneously heating an independent stream of charging stock for delivery to said enlarged zone to a temperature sufficient to cause a substantial vaporization thereof in said zone, and in introducing said heated charging stock into the enlarged zone.

2. A process of oil conversion, consisting in maintaining a body of heated hydrocarbons in an enlarged zone where substantial vaporization occurs, in maintaining said zone under a pressure below atmospheric, in subjecting the vapors to reflux condensation to condense the heavier vapors, in passing the reflux condensate in an advancing stream through a heating zone where it is subjected to cracking conditions of temperature and pressure, in delivering the heated condensate to said enlarged zone and simultaneously heating an independent stream of charging stock for delivery to said enlarged zone to a temperature sufficient to cause a substantial vaporization thereof in said zone, and in introducing said heated charging stock into the enlarged zone and in withdrawing the unvaporized oil from said enlarged zone without permitting the same to again enter either of said oil streams.

3. A process of oil conversion, consisting in maintaining a body of heated hydrocarbons in an enlarged zone where vaporization occurs, in subjecting the vapors to reflux condensation to condense the heavier fractions thereof, in passing the reflux condensate in an advancing stream through a heating zone where it is subjected to cracking conditions of temperature and pressure, in delivering the heated condensate to said enlarged zone and simultaneously heating an independent stream of charging oil for delivery to said enlarged zone to a temperature sufficient to cause a substantial vaporization thereof in said zone, in introducing said heated charging stock into the enlarged zone, and in main-

taining said enlarged zone and reflux condenser under a vacuum.

4. A process of oil conversion consisting in maintaining a body of heated hydrocarbons in an enlarged zone where substantial vaporization is permitted, in subjecting the vapors to reflux condensation to condense the heavier fractions thereof, in passing the resulting reflux condensate in an advancing stream through a heating zone where it is subjected to cracking conditions of temperature and pressure, in delivering said heated condensate to said enlarged zone and simultaneously heating an independent advancing stream of charging stock to be delivered to said enlarged zone at a temperature lower than the temperature of the stream of reflux condensate but sufficiently high to cause a substantial vaporization of the charging stock in said enlarged zone, and in maintaining a pressure in said enlarged zone substantially below atmospheric.

5. A process of oil conversion, consisting in continuously introducing into an enlarged zone heated hydrocarbon materials, and in which zone vaporization occurs, in subjecting such vapors to reflux condensation to condense the heavier fractions thereof, in passing reflux condensate in an advancing stream through a heating zone where it is subjected to cracking conditions of temperature and pressure, in transferring the heated condensate to said enlarged zone, in simultaneously heating a separate stream of charging oil for delivery to said enlarged zone to a temperature sufficient to cause a substantial vaporization thereof in said zone and in maintaining the oil in said enlarged zone under a vacuum to promote vaporization of a substantial portion thereof.

6. A process of oil conversion comprising maintaining a body of heated hydrocarbons in an enlarged zone where substantial vaporization occurs, maintaining the oil in said zone under a pressure below atmospheric, subjecting vapors evolved from the oil to reflux condensation to condense heavier vapors, simultaneously advancing independent streams of relatively heavier and substantially more refractory lighter hydrocarbon oils through a heating zone wherein such heavier and lighter oils are subjected to respectively relatively lower and higher cracking conditions of temperature and superatmospheric pressure, delivering the separately heated streams of relatively heavier and lighter hydrocarbons to the body of oil in said enlarged zone to be commingled therewith.

GUSTAV EGLOFF.
